BEARING PILE

John P. Emshwiller, Riverdale, Md.

Application May 5, 1950, Serial No. 160,202

10 Claims. (Cl. 61—53)

(Granted under Title 35, U. S. Code (1952),
sec. 266)

1

The invention described herein may be manufactured and used by or for the Government of the United States for governmental purposes without payment to me of any royalty thereon in accordance with the provisions of the act of April 30, 1928 (ch. 460, 45 Stat. L. 467).

This invention relates to piling and a method of driving piling.

It is an object of this invention to provide a pile which can be expanded at one or more predetermined locations along its length.

It is another object of this invention to provide piles having increased pulling resistance and load supporting capacity.

Other objects or advantages will be apparent or appear hereinafter.

These objects and advantages are accomplished in accordance with this invention by a pile including a pipe or tube having a plurality of substantially equal longitudinal slots symmetrically disposed in a zone about its periphery, an inner sleeve member one end of which is secured to said pipe and which is free at its opposite end, a positive stop for said sleeve secured within said pipe at a point away from said free end not further than about one-half the length of the slots.

The invention will be better understood by reference to the figures of the drawing where there are shown presently preferred embodiments of the invention. Figure 1 is a partly sectionalized view in elevation of a slotted zone along the length of a pipe pile. Figure 2 is a vertical partially sectionalized view of an expanded pile. Fig. 3 is a view like Fig. 1 of a modification, and Fig. 4 is an elevation of a further modification.

Referring now to Figures 1 and 2 there is shown a section of a tube or pipe pile 10 at the point along its length where its expansion is desired. Any type of hollow pile can be used in this connection regardless of cross sectional shape. Cut into the pile are a plurality of slots 11. It is presently preferred to cut these slots so that their longitudinal axis is substantially parallel to the longitudinal axis of the pile, because a greater degree of deformation can be obtained with shorter slots. Torsional reactions are also eliminated thereby preventing any tendency of the segments of the pile above and below the slots to rotate with respect to each other. Further it is considered preferable to have the slots symmetrically disposed about the periphery of the pile so that uniform expansion will occur.

The amount of expansion of the pile is limited by the length of the slot 11 and length of travel

2

of the free end of the sleeve member 132 as will be discussed more in detail hereinafter. The force necessary to deform or expand the pile will be determined in part by the physical metallurgical characteristics of the piling, and the expansion can be controlled in piling of the same material, size, and shape which are being used in the same application by varying the length of the slots, the width of the slots, and the web thickness 12 between the slots. While in some instances it would be possible to have the slots prefabricated in the piling, the fact that their size will be varied by structural limitations it is preferable to slot the pile after determining their proper size and location. Slotting can be carried out by any of the many methods known to the art; for example, oxy-acetylene torches.

Still referring to the drawings there is shown an inner sleeve member 13 within the slotted zone. 20 The sleeve is employed to prevent inward buckling of the slot webs during driving and to positively limit the expansion at some predetermined position, and to insure concentric alignment of the tube above and below the slots after expansion. 25 The sleeve member is secured at one of its ends to the piling. In the embodiment shown in Figs. 1 and 2 of the drawings the lower sleeve end 131 and the lower end of the pile 101 are secured by a weld 14. However any other means of securing 30 the pipe and sleeve can be employed, for example, riveting, bolting, threading and the like. The opposite end of the sleeve member 132 is not secured to the piling; hereinafter this end will sometimes be referred to as the free end of the sleeve.

35 A means for arresting movement of the inner sleeve member is secured within the pipe. A rigid ring 15 welded in the pipe has been found to be a satisfactory means for this purpose but other means can be substituted. The ring 15 forms a 40 shoulder 151 which when engaged by sleeve end 132 will arrest relative movement of the sleeve 13 with respect to the pile 10 and also relative movement of the pile end 101 with respect to the pile head 102 when the slotted zone is expanded 45 to the desired degree. When the pile is unexpanded, the distance between the free sleeve end 132 and shoulder 151 will fix the extent to which the slotted zone can expand. For example, if the distance between the free end 132 and the shoulder is about one-half the length of the slots 11, then the maximum buckling (i. e. pile expansion) of the web members 12 can occur. The extent of web buckling can be controlled to suit various driving conditions. In many applications 50 it is preferable to secure web buckling (pile ex-

pansion) such as shown in Figure 2. In that particular example the distance between the free end 132 and the shoulder 151 in the undriven pile was about one-fourth the slot length. It is apparent therefore that the extent of pile expansion can be controlled by properly establishing the distance between the sleeve end and positive stop.

As shown in Figure 1 the sleeve 133 has several parts or openings cut through it lying substantially within the slotted zone of the pile. Such parts can be employed to fill the bulb formed when the pile is expanded with concrete or other grouting material. This practice will result in piles of even greater strength and resistance.

Another embodiment of the invention as illustrated in Fig. 3 involves securing one end of the inner sleeve member 13' within the pile 10' at some point above the slots 11' and having its lower end act as the free end capable of coming into engagement with the positive stop means 15', i. e., a mere transposition of the parts shown in Figure 1.

Another embodiment of the invention involves securing expandible tips and/or intermediate expandible sections to concrete or wood piling to form a composite pile.

The driving of the piling of this invention will vary with the nature of the application. If they are to be driven to bed rock before expanding the pile, and in being so driven the pile passes through a soil strata capable of causing the pile to expand, then it is preferable to employ a pilot pile extending completely through the hollow piling and sleeve member so that none of the driving forces affect the web members. When bed rock is reached the pilot pile is withdrawn, and the pile driving hammer is permitted to operate against the pile head. These forces will cause the pile to begin expanding (i. e. buckle the web members) because the slotting has weakened the zone of the pile which is desired to be expanded. By continuing driving on the pile head, expansion of the pile will continue until the free end of the inner sleeve comes into engagement with the stop means. At this point expansion is complete and the pile end cannot move relative to the pile head. A pilot pile is also of use in driving through temporary obstructions. In driving to rock through soft soil, the pilot pile is not required.

Under certain soil conditions and when a pilot pile is not used, the frictional resistance of the pile to driving will be sufficient to cause expansion of the pile without reaching bed rock. This can also be accomplished by closing up on the opening of the lower end of the pile thereby adding end or point bearing to friction resistance to cause expansion. It will be apparent that it is possible to design the slot and webs of the piling so that expansion will not occur until an elevation has been reached which will provide the desired pulling and load supporting characteristics.

In some instances where the piling is to pass through various types of substrata it may be desirable to have the piling expanded at more than one elevation. This can readily be done as indicated in Fig. 4 by putting a plurality of slotted zones 11" along the pile 10" at the predetermined points where expansion is desired. In such instances expansion of the various zones can be accomplished simultaneously or separately at the various levels.

The expanded piling described herein will give greatly increased resistance to pulling forces and increase the load supporting capacity of the piling even in poor soil conditions.

5 While the piling as particularly described includes a movable sleeve and a positive stop for said sleeve it is possible in certain applications to eliminate these elements and merely use a slotted pile. Such piles can be expanded by driving to bed rock, permitting the end resistance of the rock to effect pile expansion.

10 Expansion of the pile at one or more of the slotted zones can also be accomplished by mechanical means such as are disclosed in my co-pending applications Serial No. 160,201, filed May 5, 1950, and Serial No. 160,203, filed May 5, 1950.

15 Since many widely differing embodiments of the invention will occur to one skilled in the art, 20 it is not to be construed as limited to the specific details illustrated and described herein, and various changes can be made therein without departing from the spirit and scope thereof.

What is claimed is:

- 25 1. A pile including a pipe having a plurality of substantially equal longitudinal slots symmetrically disposed in a zone about its periphery, an inner sleeve member at least partially within said slotted zone one end of which is secured to said pipe outside said slotted zone and which is free at its opposite end, a positive stop for said sleeve secured within said pipe at a point away from said free end not further than about $\frac{1}{2}$ the length of the slots.
- 30 2. A pile including a pipe having a plurality of substantially equal longitudinal slots symmetrically disposed in a zone about its periphery, an inner sleeve member secured to said pipe at a point below the bottom of said slots and free at its upper end, and a positive stop for said sleeve secured within said pipe at a point above the free end of said inner sleeve member not greater than about $\frac{1}{2}$ the length of said slots.
- 35 3. An expanding pile including a pipe having a plurality of substantially equal longitudinal slots symmetrically disposed in a zone about its periphery, an inner sleeve member secured to said pipe at a point below the bottom of said slots and free at its upper end, and a positive stop for said sleeve secured within said pipe at a point above the free end of said inner sleeve member not greater than about $\frac{1}{2}$ the length of said slots.
- 40 4. An expanding pile including a pipe having a plurality of substantially equal longitudinal slots symmetrically disposed about its periphery, an inner sleeve member secured at its upper end at a point above said slots to said pipe and free at its lower end, a positive stop for said sleeve secured within said pipe at a point below the lower end of said sleeve and not further from said free end than about $\frac{1}{2}$ the length of said slots.
- 45 5. The pile of claim 1 having a plurality of slotted zones along its length.

- 50 6. A pile comprising an open bottomed hollow tube of a strength adapting it to be driven to a bearing in terrestrial strata and having a plurality of longitudinal slots symmetrically disposed in a zone about its periphery and dividing said zone into webs capable of resisting bulging under the driving of the pile until a predetermined bearing resistance is encountered and of then bulging under continued application of driving force to expand the pile without loss of bearing on the underlying structure, whereby the driving of the pile through overburden involves only a minimum displacement of overburden and hence a minimum bearing resistance until a strata is reached offering the desired bearing resistance to the limited annular end area of the hollow pile.
- 55 7. A pile comprising a hollow tube of a strength adapting it to be driven to a bearing in terres-

- 60 75 8. A pile comprising a hollow tube of a strength adapting it to be driven to a bearing in terres-

trial strata and having a plurality of longitudinal slots symmetrically disposed in a zone about its periphery and dividing said zone into webs capable of resisting bulging under the driving of the pile until a predetermined bearing resistance is encountered and of then bulging under continued application of driving force to expand the pile without loss of bearing on the underlying structure, said pile having within its tube initially spaced abutment means brought into engagement on the buckling of the slotted portion for limiting such buckling and transferring vertical loads applied to the top of the pile to the underlying bearing strata.

7. A pile according to claim 6 in which said abutment means comprises one abutment element carried by the tube and spaced from one end of said slotted zone and a second abutment element compressing a sleeve secured to said tube beyond the other end of said slotted zone and extending across the slotted zone in the buckled condition thereof.

8. A pile according to claim 6 in which said abutment elements are initially spaced apart by a distance not greater than about one-half the length of said slots.

9. A pile according to claim 7 in which said

sleeve is perforated to permit filling material to pass therethrough between the interior of said sleeve and the space within the expanded slotted portion.

10. A method for installing piling that comprises slotting a hollow open bottomed metallic pile in a zone about its periphery with slots of a frequency and length predetermined to impart to the slotted section a resistance to buckling to correspond with a desired bearing resistance, driving the pile until such bearing resistance is encountered, and thereafter applying additional driving force to said pile to cause said slotted zone to expand and buckle while maintaining the attained bearing resistance.
